(57) **CLAIM**

The ornamental design for a watercraft reflector device, as shown and described.

DESCRIPTION

FIG. 1 is a front elevated view of a watercraft reflector device showing my new design;

FIG. 2 is a rear elevated view of the watercraft reflector device;

FIG. 3 is a side elevated view of the watercraft reflector device;

FIG. 4 is a top plan view of the watercraft reflector device; and,

FIG. 5 is a perspective view of the watercraft reflector device.
